UNITED STATES PATENT OFFICE.

JOHN W. BATES, OF BROOKLYN, NEW YORK.

SANDING ATTACHMENT FOR CARS.

SPECIFICATION forming part of Letters Patent No. 414,895, dated November 12, 1889.

Application filed September 2, 1889. Serial No. 322,664. (No model.)

To all whom it may concern:

Be it known that I, JOHN W. BATES, of Brooklyn, in the county of Kings and State of New York, have invented a new and Improved Sanding Attachment for Cars, of which the following is a full, clear, and exact description.

The object of the invention is to provide a new and improved sanding attachment especially adapted for street-cars and enabling the driver to conveniently sand the rail in front of the wheel whenever desired, at the same time preventing all clogging of the sand in the discharge-spout of the sand-box.

15 The invention consists of an agitating-rod passing through the spout of the sand-box and connected with the spout-valve.

The invention also consists of certain parts and details and combinations of the same, as 20 will be fully described hereinafter, and then pointed out in the claims.

Reference is to be had to the accompanying drawings, forming a part of this specification, in which similar letters of reference indicate 25 corresponding parts in all the figures.

Figure 1 is a sectional side elevation of the improvement as applied to a car, parts of the latter being broken away, and Fig. 2 is an enlarged section of the spring and its casing.

30 The improved sand attachment A is provided with the usual sand-box B, located under the seat of the car and provided with a downwardly-extending spout C, terminating a short distance above the rail in front of the car-wheel. On the lower end of the spout C is hinged a valve D, arranged in an inclined 35 position and adapted to close the lower end of the spout.

The valve D is pivotally connected with 40 one end of a rod E, passing through a barrel F, in which is held a spring G, coiled around part of the rod E, secured by one end on the said rod and resting at its other end on a cap F', screwing on one end of the barrel F. The 45 other end of the latter is also closed by a cap F'', so as to prevent dust from passing into the barrel F. At the same time the two caps F' and F'' form a convenient bearing for the rod E. The barrel F is fastened by suitable clips to the under side of the car-body. The rod E extends under the platform of the 50 car, and is pivotally connected at its outer

end with one arm of a bell-crank lever H, fulcrumed under the front end of the platform and pivotally connected at its other end 55 with an upwardly-extending rod I, passing through the bottom of the platform and carrying at its outer upper end a knob J, adapted to be pressed on by the foot of the driver standing on the front platform of the car. 60 The spring G presses against the rod E in the direction of the arrow a', so that the valve D remains seated on the lower end of the spout C until the rod E is operated on by the driver pressing his foot on the knob J of the 65 rod I. When the operator does this, the rod E is moved in the inverse direction of the arrow a' against the tension of the spring G, and the valve D is swung downward and forward, so that the lower end of the spout C is 70 opened and the sand contained in the said spout can run down over the inclined valve D onto the track-rail.

In order to prevent clogging of the sand in the spout C and the sand-box B, an agitating-rod K is connected with the inner face of the valve D, said rod projecting through the spout C and partly into the sand-box B. The agitating-rod K is preferably crooked, as shown in Fig. 1, so as to agitate the sand thoroughly 80 when the valve D is opened or closed. As soon as the operator releases his pressure on the knob J the spring G forces the rod E in the direction of the arrow a', so that the valve D is again seated on the lower end of the 85 spout C.

It will be seen that when the valve D is swung downward and outward and seated again, as above described, the agitating-rod K is moved down and up in the said spout C, 90 whereby the sand is agitated and prevented from clogging.

It is to be understood that such a sanding attachment is arranged on each end of the car under one of the front and rear wheels. 95

Having thus fully described my invention, I claim as new and desire to secure by Letters Patent—

1. In a sanding attachment for cars, the combination, with the spout-valve hinged on the sand-box spout, of an agitating-rod held on the said valve and passing into the said spout, substantially as shown and described. 100

2. In a sanding attachment for cars, the com-

bination, with the spout-valve hinged on the sand-box spout, of an agitating-rod held on the said spout-valve and passing into the said spout, and means, substantially as described, 5 for opening and closing said valve, as set forth.

3. A sanding attachment for cars, comprising a sand-box and an outlet-spout secured thereto, a valve hinged on the lower end of the 10 said outlet-spout and adapted to be opened and closed, and an agitating-rod held on the said valve and projecting into the said spout, substantially as shown and described.

4. A sanding attachment for cars, comprising a sand-box and outlet-spout secured thereto, a valve hinged on the lower end of the 15 said outlet-spout and adapted to be opened and closed, an agitating-rod held on the said valve and projecting into the said spout, a rod 20 pivotally connected with the said valve, and

a spring pressing against the said rod to hold the said valve on its seat, substantially as shown and described.

5. A sanding attachment for cars, comprising a sand-box and outlet-spout secured thereto, a valve hinged on the lower end of the 25 said outlet-spout and adapted to be opened and closed, an agitating-rod held on the said valve and projecting into the said spout, a rod pivotally connected with the said valve, 30 a spring pressing against the said rod to hold the said valve on its seat, a bell-crank lever pivotally connected with the said rod, and a foot-piece connected with the said bell-crank lever and under the control of the driver, 35 substantially as shown and described.

JOHN W. BATES.
